(57) **CLAIM**

The ornamental design for a trash can as shown and described.

DESCRIPTION

FIG. 1 is a perspective view of a trash can showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

In FIG. 9, the trash can has been shown separately from the inner can and lid to show aspects of the design that may not be apparent in the other views.

The broken lines depict portions of the trash can that form no part of the claimed design.

1 Claim, 9 Drawing Sheets
